UNITED STATES PATENT OFFICE

157,735

PORTABLE ELECTRIC LAMP

Paul C. Calissi, Darby, Pa.

Application April 6, 1949, Serial No. 1,833

Term of patent 7 years

(Cl. D48—20)

To all whom it may concern:

Be it known that I, Paul C. Calissi, a citizen of the United States and a resident of Darby, county of Delaware, State of Pennsylvania, have invented a new, original, and ornamental Design for a Portable Electric Lamp, of which the following is a specification, reference being had to the accompanying drawings forming a part thereof, wherein:

Figure 1 is a front elevational view of a portable electric lamp showing my new design; and

Figure 2 is a side elevational view thereof.

The characteristic features of the present design reside in the portions shown in full lines in the drawing.

I claim:

The ornamental design for a portable electric lamp, substantially as shown and described.

PAUL C. CALISSI.
